(57) CLAIM

The ornamental design for a pet bowl, as shown and described.

DESCRIPTION

FIG. 1 is a front isometric view of the pet bowl of the present invention;

FIG. 2 is front view thereof, the rear view being a mirror image thereof;

FIG. 3 is a left-side view, the right-side view being a mirror image thereof; and,

FIG. 4 is a top plan view thereof.

The broken lines shown in the interior illustrate portions of the pet bowl that form no part of the claimed design. The dot-dashed broken lines represent the bounds of the claim and form no part of the claimed design.
